CHARLES GAUTIER, OF WASHINGTON, DISTRICT OF COLUMBIA.

Design No. 2,911, dated February 4, 1868.

DESIGN FOR A TRADE-MARK.

The Schedule referred to in these Letters Patent and making part of the same.

TO ALL WHOM IT MAY CONCERN:

Be it known that I, CHARLES GAUTIER, of the city of Washington, in the District of Columbia, have originated and designed a new Design for a Trade-Mark, of which the following is a full, clear, and exact description, reference being had to the accompanying drawings, making part of this specification.

This design is intended for a label to be attached to a bottle, and consists of two parts. On one end of the label is a monogram, composed of the letters C G N W B, in colors on an ornamented black ground. Above the monogram, the words "Charles Gautier," and below, the words "Native Wine Bitters," and "C. Gautier, 252 Pennsylvania av., Washington, D. C.," the first two lines in gold letters, the last in black. On one side of the monogram is the word, "trade" and on the opposite side the word, "mark" both intended to be printed in gold letters. On the opposite end of the label is a letter-press inscription, as set forth in the annexed specimen.

What I claim as my invention, and desire to secure by Letters Patent, is—

The design for a trade-mark, herein set forth and shown.

In testimony whereof, I have signed my name to this specification in the presence of two subscribing witnesses.

C. GAUTIER.
